LOOP-TAKER FOR SEWING MACHINES

Max L. Waterman, Fairfield, Conn., assignor to
The Singer Manufacturing Company, Elizabeth,
N. J., a corporation of New Jersey

Application August 25, 1937, Serial No. 160,772

10 Claims. (Cl. 112—184)

This invention relates to sewing machines and more particularly to improvements in sewing machines of the type employing a loop-taker actuated to cast needle-thread loops around a thread-carrier journaled in the loop-taker and restrained against rotation about its axis.

The present invention has for its primary object to provide an improved construction for effecting an unobstructed passage for the needle-thread loops around the thread-carrier of a loop-taker, which improved construction operates with a minimum amount of noise when engaging the thread-carrier for the purpose of restraining the same against rotation.

Another object of the invention is to provide a loop-taker having journaled therein a thread-carrier which, by its motion, draws thread from the lower thread mass, producing slack in said thread, thereby to facilitate the passage of the needle-thread between the lower thread and the lower edge of the needle-aperture in the throat-plate during the formation of the stitches.

Other objects and advantages will be apparent from a complete description of one embodiment 25 of the invention shown in the accompanying drawings, in which—

Fig. 1 is a front elevation of a portion of a sewing machine head and bed showing the loop-taker mechanism and the usual reciprocatory needle at substantially the lower end of its stroke.

Fig. 2 is a top-plan view showing the gear drive for the loop-taker and a portion of the feeding mechanism.

Fig. 3 represents a substantially central, longitudinal section taken along the line 3—3, Fig. 2.

Fig. 4 represents a portion only of Fig. 3, showing the thread-carrier turned clockwise 180 degrees.

Fig. 5 represents a central vertical section of the loop-taker body, illustrating the inclined raceway.

Fig. 6 represents a vertical section taken along the line 6—6, Fig. 4, showing the preferred shape of the slots formed in the thread-carrier.

Fig. 7 is a perspective view of a portion of the cloth-plate with the slide-plate removed, showing the loop-taker in the position in which maximum thread pull-off occurs.

Fig. 8 is an enlarged longitudinal view, partly in section, taken substantially along the center-line of the needle-aperture, showing the slack in the lower thread which facilitates the passage of the needle-thread between the lower thread and the lower edge of the needle-aperture just prior to the setting of the stitch by the take-up.

Fig. 9 is a view similar to a portion of Fig. 8, showing the usual taut lower thread of a conventional sewing machine.

Fig. 10 is a disassembled perspective view of the loop-taker and thread-carrier, showing the latter removed from the loop-taker.

According to the preferred embodiment of the invention illustrated, the sewing machine comprises a frame including a bracket-arm head 1 and bed-plate 1' having a reciprocating needle 2, feed-dog 3, slide-plate 4, and throat-plate 5, all of common form.

Journaled in a bushing 6 secured in a supporting lug 7 depending from the bed-plate 1' is an actuating shaft 8 which drives the vertical-axis tubular loop-taker shaft 9 through the spiral gears 10 and 11 which have a ratio such that the loop-taker shaft 9 is rotated twice for each rotation of the actuating shaft 8.

The loop-taker shaft 9 is preferably journaled in suitable bushings 12 fixed in the vertically spaced horizontally disposed limbs 13, 14 of the loop-taker supporting bracket 15. The bushings 12 are prevented from turning in their respective supporting limbs by the set-screws 16. Disposed between the limbs 13, 14 of the bracket 15 is the driven spiral gear 11 which is fastened securely upon the loop-taker shaft 9 by a set-screw 17.

The loop-taker supporting bracket 15 is provided at its rearward end with a split bearing-boss 18 adjustably clamped upon the bushing 6 by a screw 19. At its forward end, the bracket 15 is formed with a foot 20 having an upper face secured by a screw 21 against a seat afforded by a horizontally flattened lower lug, (not shown), depending from the bed-plate 1'. In order to provide for adjustment of the bracket 15 toward and from the path of needle-reciprocation, the screw 21 passes through a slot 22 provided in the bracket-foot 20.

It is to be understood that the loop-taker supporting bracket 15 forms no part of this invention, the bracket being illustrated and described in detail in the United States patent to G. M. Eames, No. 1,155,051, issued Sept. 28, 1915.

Formed integral with the upper end of the loop-taker shaft 9 is the loop-taker body 23 which is substantially cup-shaped, having the usual loop-seizing beak 24 formed in its wall. The loop-taker body 23 is formed also with the usual annular raceway 25 which receives the annular bearing-rib 26 of the thread-carrier 27. The thread-carrier 27 is preferably held in the loop-taker body 23 against displacement by means of an arcuate member or 55

gib 28 secured to the loop-taker body 23 by a pin 29 and a screw 30.

To insure that the thread-carrier 27 is restrained from rotating with the loop-taker body 23, I have preferably formed in the bottom of the thread-carrier two elongated slots 31, 32 positioned at diametrically opposite points, (see Fig. 4). As the loop-taker is rotated, each of the slots 31, 32 engages its respective one of two upstanding detaining teeth 33, 34 formed upon the top of a stationary flat disk 35 disposed within and at the bottom of the cup-shaped body of the loop-taker. Extending downwardly from the bottom of the disk 35 is a rod 36 disposed within the axial bore 37 of the loop-taker shaft 9. As clearly illustrated in Fig. 3, the lower end of the rod 36 extends below the lower end of the shaft 9 and is clamped against rotation preferably by the split bushing 38 supported in the split lower end 39 of the L-shaped bracket 40 which is rigidly secured to the loop-taker supporting bracket 15 by the screw 41. The clamping screw 42 maintains the split bushing 38 in tight gripping engagement with the lower end of the rod 36.

It will be seen by reference to Figs. 3 and 4 that as the loop-taker is rotated the inclination of the raceway 25 causes the non-rotating thread-carrier 27 to progressively tilt in all directions with respect to the axis of movement of the loop-taker. Hereinafter this progressively tilting motion of the thread-carrier will be referred to as a "wabbly" motion. The wabbly motion of the thread-carrier effects an alternate engagement and disengagement of the walls of the elongated slots 31, 32 in the thread-carrier 27 with the detaining teeth 33, 34 on the disk 35. It will be understood that when one of the detaining teeth is temporarily disengaged, the needle-thread loop can unrestrictedly pass between the bottom of the thread-carrier 27 and the top of the disengaged detaining tooth while the second detaining tooth prevents the thread-carrier from rotating. Upon further turning of the loop-taker, the second detaining tooth is disengaged from the thread-carrier after the first detaining tooth engages it. This alternate engagement and disengagement of the thread-carrier slots with the detaining teeth is so timed that the needle-thread loops may be cast unobstructedly around the thread-carrier. The detaining teeth 33, 34 are of sufficient height so that the thread-carrier during its wabbly movement is at no time free to rotate with the loop-taker.

It has been found that due to the wabbly motion imparted to the thread-carrier a definite pull-off action on the lower thread occurs once during each stitch-forming cycle. This pull-off action occurs during the time in which the thread-carrier is moving bodily away from the path of needle-reciprocation. Maximum pull-off action occurs when the loop-taker and thread-carrier are in the position illustrated in Fig. 7. In addition to the desirable pull-off action on the lower thread, the wabbly motion of the thread-carrier also produces slack in the lower thread, as shown in Fig. 8. This slack in the lower thread is produced after the pull-off action occurs and during the time the thread-carrier moves bodily toward the path of needle-reciprocation. As clearly shown in Fig. 8, this desirable slack in the lower thread T' readily permits the loop of the needle-thread T'' to pass between the lower thread T' and the edge 43 of the needle-aperture 44 in the throat-plate 5. In Fig. 9 it can be seen that, in the conventional sewing ma-

chine, the lower thread T' is taut and in order for the loop of the needle-thread T'' to pass by the edge 43 it is necessary for the take-up to exert a considerable tension on the thread T''.

By reference to Fig. 6, it will be observed that the side-walls of the slots 31, 32 formed in the bottom of the thread-carrier 27 are upwardly flared, and the effective side-walls of the detaining teeth 33, 34 are flat and disposed at right angles to the top surface of the disk 35. Obviously, the side-walls of the detaining teeth may be downwardly flared and the side-walls of the slots in the thread-carrier may be vertical without in any way affecting the operation of the mechanism. It has been found that by suitably shaping the slots and the detaining teeth a minimum amount of play is afforded between the two, thereby resulting in a very quiet operation of the mechanism at comparatively high speeds.

From the foregoing description, it is obvious that the present invention contemplates an improved rotation-restraining means for the thread-carrier of a loop-taker, and by properly shaping the slots in the thread-carrier and the surfaces of the detaining teeth a mechanism is produced which functions efficiently and with a minimum amount of noise.

The invention is not to be understood as limited to the details of construction and arrangement of parts shown and described as a preferred embodiment of the invention, as various modifications may obviously be made by those skilled in the art within the spirit and scope of the invention.

Having thus set forth the nature of the invention what I claim herein is:—

1. A loop-taker for sewing machines comprising a body-portion having an axis of rotation, a thread-carrier journaled in said body-portion, the bearing between the two being disposed in a plane inclined to the axis of rotation of said loop-taker whereby to cause the thread-carrier to move with a wabbly motion when the loop-taker is actuated, and means for restraining said thread-carrier against turning movement with the loop-taker.

2. A loop-taker for sewing machines comprising a body-portion having a raceway formed therein, said raceway being disposed in a plane inclined to the axis of movement of said body-portion, a thread-carrier journaled in said raceway, and means for restraining said thread-carrier against turning movement with the loop-taker.

3. A loop-taker for sewing machines comprising a body-portion having a raceway formed therein, said raceway being disposed in a plane inclined to the axis of movement of said body-portion, a thread-carrier journaled in said raceway, and a plurality of detent means alternately engaged by said thread-carrier for restraining it against turning movement.

4. A loop-taker for sewing machines comprising a body-portion having a raceway formed therein, said raceway being disposed in a plane inclined to the axis of movement of said body-portion, a thread-carrier journaled in said raceway, and a plurality of means for restraining said thread-carrier against turning movement with the loop-taker, said means being rendered effective by the turning movement of said loop-taker to alternately engage said thread-carrier.

5. A loop-taker for sewing machines comprising a body-portion having an inclined raceway formed in said body-portion, a thread-carrier

- 5 journaled in said raceway and having formed therein a plurality of slots, and detent means alternately engaged by said slots for restraining said thread-carrier against turning movement with the loop-taker.
6. In a sewing machine, a loop-taker comprising a body-portion having an inclined raceway formed in said body-portion, a thread-carrier journaled in said raceway and having formed 10 therein a plurality of slots, and means including a plurality of detaining teeth disposed within the loop-taker body and arranged to be alternately engaged by said slots for restraining the thread-carrier against turning movement.
- 15 7. In a sewing machine, a loop-taker having a body-portion formed with an inclined raceway, a thread-carrier journaled in said raceway and having formed therein a plurality of slots, a shaft having an axial bore supporting said loop-taker, a 20 stationary rod disposed within the axial bore of said shaft and terminating in a disk, and a plurality of teeth formed on said disk, said teeth arranged to be alternately engaged by the slots in the thread-carrier for restraining the latter against turning movement.
- 25 8. In a sewing machine, a reciprocatory needle, a loop-taker cooperating with said needle in the formation of stitches, a thread-carrier so jour-
- naled in said loop-taker as to have a wabbly motion as the loop-taker is actuated, and stationary means for restraining the thread-carrier against turning movement.
9. The combination with a reciprocatory needle and a throat-plate having a needle-aperture, of a circularly moving loop-taker, a thread-carrier for the lower thread, concentrically located in said loop-taker, means for restraining the thread-carrier against turning movement, and means to 10 pull-off and give slack to the lower thread thereby to facilitate the passage of the needle-thread loop between said lower thread and the lower edge of the needle-aperture during the formation of the stitches.
10. A sewing machine having, in combination, 15 a reciprocatory needle, a circularly moving loop-taker cooperating with said needle in the formation of stitches, a thread-carrier journaled in said loop-taker, means for restraining the thread-carrier against turning movement, and means rendered effective by the turning movement of the loop-taker for progressively tilting the thread-carrier relative to the axis of movement of the loop-taker to pull off and give slack to the lower thread during each stitch-forming cycle.

MAX L. WATERMAN.
